UNITED STATES PATENT OFFICE.

RALPH CHARLES STIEFEL, OF ELLWOOD CITY, PENNSYLVANIA, ASSIGNOR
TO NATIONAL TUBE COMPANY, OF NEW YORK, N. Y., A CORPORATION
OF NEW JERSEY.

APPARATUS FOR ROLLING TUBES AND TUBULAR BODIES.

No. 813,597.

Specification of Letters Patent.

Patented Feb. 27, 1906.

Application filed February 27, 1904. Serial No. 195,522.

To all whom it may concern:

Be it known that I, RALPH CHARLES STIEFEL, a citizen of the United States, and a resident of Ellwood City, in the State of Pennsylvania, have invented certain new and useful Improvements in Apparatus for Rolling Tubes and Tubular Bodies, of which the following is a specification, accompanied by drawings.

10 This invention relates to apparatus for rolling tubes and tubular bodies; and its objects are to improve upon such machines with the aim of eliminating undue strains on the metal during the piercing process.

15 Further objects of the invention will hereinafter appear; and to these ends the invention consists of apparatus for carrying out the above objects, embodying the features of construction, combinations of elements, and 20 arrangement of parts having the general mode of operation substantially as herein-after fully described and claimed in this specification and shown in the accompanying drawings, in which—

25 Figure 1 is a top plan view of apparatus embodying the invention. Fig. 2 is a transverse sectional view on the line $x-x$ of Fig. 1. Fig. 3 is a rear elevation of the apparatus, partly in section on the longitudinal axis of 30 the mill. Fig. 4 is a diagrammatic view showing the displacement of the metal as the billet is pierced. Fig. 5 is an elevation of one of the rolls, showing its disposition relatively to the pass.

35 Referring to the drawings, the rolls A are mounted on shafts B, carried in the bearings A' and provided with the driven bevel-gears C, operated by the driving bevel-gears D on the shafts E, held in bearings F. The shafts

40 E are suitably driven from the counter-shaft G by the gearing, as shown, suitably arranged to operate the rolls A in the required direction. The driven gears C and the rolls A, as shown, have common axes, while the driving-

45 gears D have a common axis which lies in the same plane with the center line of the pass $x-x$ and at substantially right angles to said line. In order to obtain the required conditions in bevel-gear drives, it is also necessary 50 that the axis of the gears D shall intersect the axes of the rolls.

The roll-housings H have circular bases I

and are seated in sliding frames J. The roll-housings H are adjustable in their circular seats around the axis of the driving-rolls D 55 in order to give the roll-axes the required obliquity in relation to the pass. When the obliquity of the rolls is adjusted by swinging said roll-housings around the axis of the shafts E E, it will be noted that the points of 60 intersection 14 14 of the longitudinal axis of the machine with the surfaces of the rolls remain stationary relatively to the center line of the pass $x-x$.

The sliding frames J are seated in the main 65 bed K and are held in their seats by suitable guide-plates L, bolted to the main bed. The bolts O are for securely fastening the roll-housings to the sliding frames after the rolls have received the proper angular adjustment. 70 Suitable means are provided for varying the width of the pass by means of worms P and worm-wheels Q on the screws R, the mechanism being so contrived that operation of the hand-wheels S slides the frames J relatively 75 to the pass in order to vary the opening between the rolls for the admission of different sizes of billets to be pierced.

By referring to Fig. 1 it will be seen that the displacement of the metal of the billet is 80 very different from that in ordinary machines for working metal, inasmuch as the metal has to be displaced from the center of the billet toward the outside, which results in more violent strains than in ordinary metal 85 forging or rolling processes where the metal generally is compressed from the outside toward the center as it is acted upon by the hammer dies or rolls. It is therefore very important that the effect of the piercing-rolls 90 be such as to aid instead of resist the natural flow of the metal under operation during the piercing process in order to not unnecessarily increase the already severe strains naturally accruing in this method of displacing metal. 95

As the solid billet T, Fig. 4, advances between the rolls A in the direction of the arrow a it first meets the rolls at the points $b-b$. The opening between the rolls, as shown, is converging as the billet advances from $b-b$ to 100 $c-c$. From $c-c$ to $d-d$ the opening of pass is diverging; but the piercing-mandrel F', over which the billet is forced by the action of the rolls, is of such shape or conicity rela-

tively to the rolls that the transverse section of the metal of the billet formed between the mandrel and the rolls is constantly reduced in area as the billet advances over the mandrel in the diverging portion of the pass. The sectional area of the billet is therefore progressively reduced as the billet advances between the rolls. If at $b b$ the rolls advance the billet with a certain speed, at $c c$, where the sectional area of the billet is smaller, the speed at which the rolls should advance the billet ought to be substantially as much greater as the sectional area is smaller, so as not to obstruct the natural flow of the metal. The same conditions should obtain while the billet advances from $c c$ to $d d$. If the rolls were of such shape and disposition as to produce the same feed effect at all points of contact with the billet, the rolls would have the tendency of feeding or advancing much more metal at $b b$ than at $c c$ and $d d$ on account of the large sectional area at $b b$ tending to advance as fast as the much smaller area at $c c$ and $d d$. Such a condition of affairs would result in strains in the metal in addition to those which would occur if there was no effect of obstructing the natural flow of the metal corresponding to the progressively-increasing reduction of area of the billet. The arrangement and shape of the rolls according to this invention are such as to produce a progressively-increasing feeding effect as the sectional area of the billet is reduced.

In Fig. 5, $g g$ represents the center line of the pass, and $h h$ the center line of the roll. a' is the angle of obliquity of the roll relatively to the pass, and i , k , and l represent three contact-points between the roll and billet. $i m$, $k o$, and $l q$ represent the developments of the roll circumference through said contact-points, while $m n$, $o p$, and $q r$ represent the feed effects or speeds of advancement as produced by the roll at the different contact-points. It will be seen that $o p$ is greater than $m n$, while $q r$ is greater than $o p$, or, in other words, the feed effect of these rolls is increasing as the billet progresses during the same. This result is obtained with rolls which fill the following two conditions combined: first, continuously increasing in diameter in the same direction that the billet progresses between the rolls; second, the feeding or advancing of the billet from the small end toward the large end of the rolls, resulting from the universal angular position of the axes of the rolls relatively to the axis of the pass.

Obviously some features of this invention may be used without others, and the invention may be embodied in widely-varying forms.

Therefore, without limiting the invention to the constructions shown and described nor

enumerating equivalents, I claim, and desire to secure by Letters Patent, the following:

1. In a rolling-mill, the combination of two rolls forming a converging and a diverging pass, and a piercing or expanding mandrel in the pass, the two rolls being symmetrically placed on opposite sides of the axis of said mandrel and skewed in respect thereto, and having progressively-larger diameters presented to the billet as it progresses through the pass and also having greater feeding effects at the diverging portion of the pass.

2. In a rolling-mill, rolls, roll-shafts, driving-shafts, the axes of which lie in a line perpendicular to and intersecting the pass, said roll-shafts being mounted obliquely to the said driving-shafts and having driving connections therefrom, and means for adjusting the roll-shafts about the axes of the said driving-shafts.

3. In a rolling-mill, rolls, roll-shafts, driving-shafts, the axes of which lie in a line perpendicular to and intersecting the pass, said roll-shafts being mounted obliquely to the said driving-shafts and having bevel-gear connections with the driving-shafts, and means for adjusting the roll-shafts about the said driving-shaft axes.

4. In a rolling-mill, rolls, roll-shafts, driving-shafts, the axes of which lie in a line perpendicular to and intersecting the pass, said roll-shafts being mounted obliquely to the said driving-shafts, housings mounted to rock about the driving-shaft axes as centers, and driving connections between the roll-shafts and the driving-shafts.

5. In a rolling-mill, rolls, roll-shafts, driving-shafts, the axes of which lie in a line perpendicular to and intersecting the pass, said roll-shafts being mounted obliquely to the said driving-shafts, housings in which the said roll-shafts are mounted, driving connections between the roll-shafts and the driving-shafts, and means for adjusting the housings along the axial line of the driving-shafts.

6. In a rolling-mill, rolls, roll-shafts, driving-shafts, the axes of which lie in a line perpendicular to and intersecting the pass, said roll-shafts being mounted obliquely to the said driving-shafts, housings in which the said roll-shafts are mounted, driving connections between the roll-shafts and the driving-shafts, and screw connections for adjusting said housings along the axial line of the driving-shafts.

In testimony whereof I have signed this specification in the presence of two subscribing witnesses.
